FIG. 3.

FIG. 2.

FIG. 4

INVENTOR.

Robert Benjamin Davis

BY *U.G. Charles*

ATTORNEY.

UNITED STATES PATENT OFFICE

ROBERT BENJAMIN DAVIS, OF WICHITA, KANSAS

SHAVING TOILET ARTICLE

Application filed May 5, 1928. Serial No. 275,457.

The object of this invention is to provide a container for shaving cream.

A further object of this invention is to provide a container as above stated, said container so constructed that it will emit the shaving cream in desired quantities for shaving purposes.

Another object of this invention is to provide a container for shaving cream; the emitter end of which is apertured through which the cream will pass and the surface of the emitter end is convex and made irregular, hammered, or corrugated providing an uneven surface for the purpose of an effective and convenient application of shaving cream emitted for producing a lather.

Another object and purpose of this device is to provide a means whereby the shaving cream can be carried in a convenient reservoir; so arranged to be easily and conveniently applied on the face and neck effectively when shaving, without the hands and fingers necessarily being used in direct contact with shaving substances when applied.

These and other objects will be explained as this description progresses.

Referring to the drawings; Fig. 1 is a side view of the invention, partly in section, longitudinally of the container as it is made for the use of shaving cream only. Fig. 2 is a bottom view of Fig. 1. Fig. 3 is a top view of Fig. 1. Fig. 4 is a side view, partly in section, of the enclosure cap for the emitter openings. Fig. 5 is a plan view of Fig. 4. Fig. 6 is a side view, partly in section, of the emitter end of the shaving toilet article with the enclosure cap shown in Figs. 4 and 5 in place on the emitter cap.

At 10 is a tubular member slightly turned inward at the top 11. The interior of the member is threaded to receive the threads 12 which are located on an enlarged portion 13 of the tubular member 14; at 15 are shown threads on the member 14, on which is screwed a cap 16; said cap having a knurled rim edge 17 which acts as a finger grip in placing the cap on, or removing it from the element 14. At 18 is shown an emitter cap threaded on the element 10 and provided with apertures 19

through which the shaving cream is emitted. The cap is provided with a knurled ring portion 20 which acts as a finger grip in assembling or removing the cap 18 from the element 10. The face of the cap 18 is made rough by corrugating or embossing bumps or irregular protrusions thereon for the purpose of working up a good lather and working the lather well into the whiskers as the cap is rubbed over the whiskered area of the face and neck.

When the emitter is not in use, a cover cap 21 is provided and adapted to slip snugly on the cap 18 as shown in Fig. 12. The cap 21 is provided with a knurled ring portion 22 which acts as a finger grip in placing or removing the cap from the member 18.

Such modifications may be employed as lie within the scope of the appended claim, and what I claim as new, and desire to secure by Letters Patent is:

In combination with a soap container having a threaded open end portion, a cap having a threaded flange to engage on the open end of the container, the head of the cap having a plurality of perforations spaced therein and a plurality of indentures protruding outward and being distributed over the surface thereof, said cap having a cover cap adapted to frictionally engage thereon as a closing means for the perforations in the first said cap, all as and for the purpose specified.

In testimony whereof I affix my signature.

ROBERT BENJAMIN DAVIS.
